TOTALIZING MECHANISM FOR COMPUTING-MACHINES.

1,127,484.

Specification of Letters Patent.

Patented Feb. 9, 1915.

Application filed December 29, 1913. Serial No. 809,384.

To all whom it may concern:

Be it known that I, JOHN EMIL WILLIAM GREVE, a subject of the Emperor of Germany, residing at Chemnitz, Saxony, 5 have invented certain new and useful Improvements in Totalizing Mechanism for Computing-Machines, of which the following is a specification.

This invention relates to the mechanism 10 for taking the totals in computing machines, and has for its object to provide a mechanism for drawing the totals and intermediate totals in computing machines, which are provided with counting mechanisms which are transposable for the purposes of addition and subtraction, and its further purpose is to effect an automatic relation between the setting of the totalizing lever and the changing or transposing 15 lever by which the transposition of the counting mechanism is brought about. To this end, according to the present invention, such a connection is provided between the totalizing lever and transposing lever for 20 the changeable counting mechanism, that the totalizing lever, when it is set for drawing a total or intermediate total, automatically sets the transposing lever, for the counting mechanism into adding position, 25 in case said transposing lever previously stood in the position for subtraction. Simultaneously, there is brought into operation a locking mechanism, which prevents a movement of the transposing lever when 30 the totalizing lever is set. The setting of the transposing lever in the adding position by the changing of the totalizing lever, can be effected, either directly by the movement of the totalizing lever, or it can be 35 brought about by means of an intermediate connection or link which is set by the operation of the totalizing lever, so that upon the subsequent hand crank movement, the setting of the transposing lever will be effected by the crank-handle and the driving 40 mechanism of the computing machine through the medium of the above mentioned intermediate link.

One form of the invention is set forth 45 in the accompanying drawings, in which, Figure 1 is a fragmentary view, in side elevation, showing the totalizing lever and the transposing lever for the changeable counting mechanism, together with the de-

vices for connecting the two levers, Fig. 2 55 is a detail plan view, Fig. 3 shows the mechanism of Figs. 1 and 2 in other operative positions, Fig. 4 shows a side elevation of the mechanism by which only an intermediate connection is set by the totalizing lever, and Fig. 5 shows a view similar to Fig. 4 with the mechanism in another operative position.

The totalizing lever 6, (by which also the intermediate totals are made), is mounted 65 for oscillatory movement in any well known way upon a shaft 11, mounted in the frame of the computing machine in which my invention is applied, said shaft also carrying a lever 7. Said lever 7 is provided with a 70 longitudinal slot 7^a into which operatively projects a pin 5^a mounted on the lever 5, which, in turn, is secured on the shaft 8. Said shaft 8 extends transversely across the machine and carries on its opposite end a 75 second lever 4. The lever 4 is supplied with a tappet-pin 9 near its free end, and is also pivoted to a draw-bar 2, which, in turn, is pivotally connected to the transposing lever 1 of the changeable counting 80 mechanism by means of the pin 2^a and the slot 2^b.

The totalizing lever is held in its set position in any well known manner (not shown), and is released just before the end 85 of the movement of the hand-crank. During this time, the transposing lever is also locked, the pin 2^a engaging in the end of the elongated opening or slot 2^b in the draw-bar 2 (Fig. 3) whereby a setting of the 90 transposing lever from the adding to the subtracting position is impossible. However, if a person unfamiliar with the machine should endeavor to throw the lever 1 over with force, there would be a strong 95 tendency for the shaft 8 to become distorted, due to the great leverage of the lever 1 and the intermediate connections. For this reason there is preferably provided, for the relief of the shaft 8 a further locking 100 mechanism. To this end a pawl 3 is mounted for oscillatory movement in the side-frame of the machine and is provided with an upwardly extending arm 3^a whose head, by means of the spring 3^b, is kept in engagement with the pin 9, upon the arm 4, in the normal position of the totalizing lever. The pawl 3 is provided with a lockin-

jection 3^c at its free end, by which it can lock behind a pin 10 at the lower end of the lever 1.

The operation of the mechanism thus far described is as follows:—If the totalizing lever 6 is swung to the rear (to the left in the drawings) for the purpose of drawing totals or intermediate totals, then the lower end of lever 7, carried by the shaft 11, will be thrown to the right, and carries therewith the arm 4, through the connection of arm 5 and pin 5^a, and the shaft 8. If the transposing lever 1 is set in subtracting position, (as shown in dotted line position in Fig. 1), then, by means of the draw-bar 2, said lever 1 will be drawn into adding position, (solid line position of Fig. 1), when the lever 6 is thrown to the left. By the above mentioned clockwise movement, of the arm 4, the pin 9 is removed from contact with the upper arm 3^a, of the pawl 3, and the spring 3^b operates to draw the pawl upwardly, bringing the locking-projection 3^c behind the pin 10, (Fig. 3), thus preventing any accidental or mistaken return of the transposing lever to subtracting position.

In Figs. 4 and 5 is shown another form of the invention.

The parts having like reference numerals correspond to the parts of the first form described, in construction and function. The arm 4, however, is provided with an abutment 4^a, against which the projection or pin 18, carried by the bell-crank-lever 22, bears. Said bell-crank-lever 22, which is suitably mounted on the machine frame, and is drawn upwardly by means of the spring 22^a, is provided on its other arm, with a pin 22^b, over which is yoked the slot 12^b of a carrier rod 12. Said carrier-rod 12 is linked to an oscillatory arm 14, which, for example, is mounted to swing on a stub 14^c on the frame of the machine. The carrier-rod 12 is further provided with an abutment 12^a, which is adapted to operatively engage the pin 10 of the transposing lever 1. Said oscillatory arm 14 is provided with a curved-face cam element 14^a. The lever 1 carries an anti-friction roller 1^a, which is adapted to engage in the notches or recesses 13^a and 13^b formed at the ends of a trackway 13^c on the lower edge of a rock-bar 13. Said rock-bar 13 is pivotally mounted on the stub 13^c and is held in normal engagement with the roller 1^a by means of the spring 13^a. A lock-bar 17 is pivoted to one end of the rock-bar 13, said lock-bar 17 being guided by means of a pin and slot connection 17^b with the side of the machine frame. At its lower end the bar 17 is provided with a notch or recess 17^a, in which the lateral projection 16^a formed on a longitudinally mounted locking-bar 16 is adapted to engage. Said locking-bar 16 is also slidably mounted on the machine frame by means of pin

and slot connections 16^b and 16^c, and stands normally under the influence of the spring 16^d. Said spring 16^d tends to draw the locking-bar 16 to the left (Figs. 4 and 5), its movement being limited by a pin or abutment 15 on the segment 15, which is one of a plurality of such segments (not shown) mounted on the shaft 20 of the machine. Upon the segment 15 is also mounted a rocking lever 19, on one end of which is secured a tappet roller 19^a. The opposite end is attached to a contraction spring 19^b, which normally draws the lever 19 into engagement with the pin 19^c carried by the segment 15. By this arrangement, when the segment 15 turns in a clockwise direction the roller 19^a is caused to bear at the beginning against the body of the cam element 14^a of the lever 14 and turn it to one side, but upon the return of the segment, said roller can ride over the face of the cam element 14^a. The lever 14 is normally drawn to the left (Fig. 4) by means of a spring 14^b connected to the machine frame and is held in engagement with a fixed stop-pin 21, which is also suitably set in the side-frame of the machine.

In the second form above described, the arm 4 is turned to the right when the lever 6 is thrown over, in the same manner as in the first described form. Thereby the projection or abutment 4^a is withdrawn from contact with the pin 18 on the end of the bell crank lever 22, and the latter, under operation of the spring 22^a is swung upwardly. By this action, the locking-projection 12^a on the carrier-bar 12 engages the pin 10 of the transposing lever 1. If the hand-crank of the machine (not shown) is pulled, or the motor-drive of the machine, is started, as the case may be, then the segment 15 is rotated in the direction of the arrow, and pushes the lever 14 to the right, with the help of the striking-roller 19^a of the rocking-lever 19, so that the transposing lever 1 is carried out of the position of Fig. 4, which shows the subtracting position, and is placed in the position shown in Fig. 5, or the adding position. When the segment 15 turns in the direction of the arrow, then the pin 15^a retreats from the locking-bar 16, and the latter, under the action of its spring 16^d is drawn to the left, until the lateral projection or lug 16^a engages the notch or recess 17^a of the locking-bar 17, whereby the rocking lever 13 is prevented from moving. In this manner, the transposing lever 1 is locked in the position of Fig. 5, the roller 1^a being engaged with the notch or recess 13^a, and before the backward movement of the hand crank, the lever 1 cannot be caused to assume any other position. This locking only occurs, however, after a complete transposition has taken place, since during the period of transposing movement the lever 13 is elevated by reason of the movement of 13^b

the roller 1^a over the track portion 13^e, the lock-bar 17 being also elevated thereby to such an extent that the projection 16^a cannot enter into engagement with the recess 17^a.

The mechanism of this invention, in its various forms, can obviously be adapted for use in machines where a key is used in place of a totalizing lever. Furthermore, 10 the invention can also be adapted for use in connection with non-printing computing machines, in order in such machines to secure the zero setting, without being compelled to transpose the counting mechanism 15 by hand from the subtracting position to the adding position.

What I claim as my invention is:—

1. In a computing machine, the combination with a lever for operating the totalizing 20 mechanism of the machine, of a lever for rocking the counting mechanism into adding or subtracting positions, and means operative between the totalizing lever and said counting-mechanism rocking lever to swing 25 the latter to adding position and there positively lock it during a totalizing operation started by said totalizing lever.

2. In a computing machine, the combination with a lever for operating the totalizing

mechanism of the machine, of a lever for 30 rocking the counting mechanism into adding or subtracting position, a mechanism released by said totalizing lever on an operative stroke to return said counting mechanism rocking lever to adding position, 35 means for actuating said return mechanism and means also operated by said return mechanism actuating means to lock said counting mechanism rocking lever during a totalizing operation.

3. In a computing machine, the combination with a lever for operating the totalizing mechanism of the machine, of a lever for 40 rocking the counting mechanism into adding or subtracting position, a normally inoperative connection between the totalizing lever and said counting mechanism rocking lever for returning the latter to adding position when the former is set to draw a total, 45 and means for locking said counting mechanism rocking lever in its adding position during a totalizing operation.

In testimony whereof I affix my signature in presence of two witnesses.

JOHN EMIL WILLIAM GREVE.
